(Cl. D56—4)

To all whom it may concern:

Be it known that we, Jacques Martial and Robert C. Scull, citizens of the United States, residing in the Borough of Manhattan, city, county, and State of New York, have invented a new, original, and ornamental Design for a Combination Radio and Record Player, of which the following is a specification, reference being had to the accompanying drawing, forming part thereof.

Fig. 1 is a perspective view of a combination radio and record player showing our new design;

Fig. 2 is a front elevational view;

Fig. 3 is a side elevational view; and

Fig. 4 is a top plan view thereof.

We claim:

The ornamental design for a combination radio and record player, as shown.

JACQUES MARTIAL.
